(57) **CLAIM**

The ornamental design for a steam iron with brush, as shown and described.

DESCRIPTION

FIG. 1 is a perspective view taken from the front, top, and right side of a steam iron with brush illustrating our new design;

FIG. 2 is a right side elevation view thereof;

FIG. 3 is a front elevation view thereof;

FIG. 4 is a left side elevation view thereof;

FIG. 5 is a top plan view thereof;

FIG. 6 is a bottom plan view thereof; and,

FIG. 7 is a rear elevation view thereof.

The crosshatching on the bottom of the iron is partially shown for ease of illustration and is understood to repeat throughout the circumscribed area. The broken-line structure shown on the rear on the iron is for illustrative purposes only and forms no part of the claimed design.
